INVENTOR.

BY ATTORNEY

UNITED STATES PATENT OFFICE.

ROBERT C. ALLEN, OF ESSINGTON, PENNSYLVANIA, ASSIGNOR TO WESTINGHOUSE GEAR AND DYNAMOMETER COMPANY, A CORPORATION OF PENNSYLVANIA.

GEARING.

Application filed September 29, 1920. Serial No. 413,640.

To all whom it may concern:

Be it known that I, ROBERT C. ALLEN, a citizen of the United States, and a resident of Essington, in the county of Delaware and State of Pennsylvania, have invented a new and useful Improvement in Gearing, of which the following is a specification.

This invention relates to gearing and particularly to gearing of the floating frame 10 type.

One of the most important advantages of floating frame gearing is its relatively light weight. Floating frame gearing may be made lighter in weight for a given capacity 15 than other gearing for the reason that the floating frames are self-aligning and automatically distribute the load uniformly along the length of the gearing. In order to accomplish the same efficient distribution 20 of load with ordinary or so-called rigid gearing, it is necessary to make the gear casing or frame quite heavy and strong so that the relative position of the supports for the gear members may not change, and of 25 course it is necessary to initially align the gear members very accurately. In floating frame gearing there is not only a saving in weight but also in cost as the initial alignment does not have to be so accurately established as is necessary with rigid gearing. This, of course, is because the floating frames permit the gear members to automatically align themselves and thereby insure a uniform distribution of load.

35 My invention contemplates a new and improved floating frame construction for gearing which emphasizes the advantage above referred to, that is, which is more flexible than other floating frame gearing now in use and known to me. In ordinary floating frame gearing the floating frame is usually mounted on a flexible member such as a section of I-beam which permits a movement of the floating frame sufficient to compensate for deflections during the operation 40 of the gears. I contemplate a floating frame construction which is provided with both flexible supports, such as I-beams, and pivotal supports such as bearings. When the 45 gearing is under load the friction of rest prevents the pivotal supporting means from functioning and deflections are compensated for through the flexibility of the I-beams. However, the bearings provide for deflec-

tions under no load such as those caused by 55 the setting up and initial adjustment of the gear members. It is evident that such a construction is unusually flexible and that it is free to automatically align itself so as to compensate for minor inaccuracies in workmanship or alignment, or due to any reasonable deflection of the casing or gear members either under load or during transportation and installation. I also contemplate a 60 construction which permits a more universal 65 compensating movement than has heretofore been employed in gearing.

An object of my invention is to produce a new and improved floating frame construction for gearing which equalizes a load 70 imposed upon the gearing more thoroughly than other floating frame constructions now in use and known to me.

A further object is to produce a new and improved gearing which may be more easily 75 and quickly constructed than other gearing of the same efficiency and capacity now in use and known to me.

A further object is to produce a new and improved mounting means for gearing 80 whereby a gear member may be mounted so as to facilitate the production of gearing and to more thoroughly distribute the load imposed on the gearing when in operation than is accomplished with other floating 85 frame constructions now in use and known to me.

These and other objects which will be made apparent throughout the further description of my invention are attained by 90 means of apparatus embodying the features herein described and illustrated in the drawings accompanying and forming a part hereof.

In the drawings: Fig. 1 is a diagrammatic elevation of a floating frame construction embodying my invention, a part of the apparatus being illustrated in section.

Fig. 2 is a plan view of the floating frame 100 illustrated in Fig. 1.

Fig. 3 is a sectional view of a part of the floating frame illustrated in Fig. 1.

Fig. 4 is a perspective view of one half of the floating frame illustrated in Figures 1 and 2.

In the drawings I have illustrated a floating frame construction suitable for mounting a divided pinion 5 of the double helical

type. The pinion illustrated is made of similar halves on which the teeth are inclined in opposite directions in the usual manner, for the purpose of balancing the end thrusts. As shown, the pinion halves are formed on a single hollow shaft 6 which is mounted in two vertical rectangular frames 7 in suitable bearings 8, one of which I have illustrated at each end of each frame. 5 A half of the pinion is adapted to operate within each frame. As shown in Fig. 4, the pinion 5 meshes with a large gear 9, which, of course, is similarly divided into halves, only one of which is illustrated in the drawing. 10

The rectangular frames 7 are mounted, as shown, on separate floating frames 10 by means of struts 11. The floating frames 10 are, in turn, mounted on the opposite ends 20 of a third and larger floating frame 12. The struts 11 are illustrated as pivotally connected with the rectangular frames 7 immediately below the bearings 8, and as similarly connected to the ends of the floating frames 10. As illustrated, two struts are provided at each end of each rectangular frame 7, one being located at the front and the other at the rear. That is, each rectangular frame is supported on its individual floating frame by four pivotally connected struts as shown in Fig. 4. 25

The small floating frames 10 are illustrated as pivotally mounted in bearings 13 which rest on supports 14 of I-beam section 35 formed or mounted on the ends of the large floating frame 12. The latter is illustrated as mounted in a similar manner in pivotal bearings 15 which are supported on sections of I-beams 16. The pivotal mounting for 40 all of the floating frames is preferably of the spherical seated type, for example, as illustrated in Fig. 3, so that the floating frames may be free to turn in any direction to a limited extent.

45 As illustrated in Fig. 1, the pinion 5 is driven by means of a shaft 17 which extends through the hollow shaft 6 and is attached to the latter at the end opposite from its driving connection. This construction provides for a relatively long flexible driving shaft without detracting from the compactness of the installation. If desired, the shaft 6 may be made in two independent sections separately driven, so that each pinion half will be capable of independent motion. 50

In Fig. 2, I have shown means for holding the pinion 5 in operative relation with the gear 9. As illustrated an individual 55 horizontal adjustable lever 18 is attached to each end of each floating frame 7 and it is pivotally mounted on the end of a horizontal adjustable arm or stud 19. The pivotal connection 20 is located at the center 60 of the lever 18 and it is preferably of the

spherical seated type such as is illustrated in Fig. 3. The outer end of the arm or stud 19 is shown as provided with threads 21 which are engaged by a nut 22. As illustrated, the nut 22 is mounted in a fixed position in the casing 23, which encloses the gears, and it is adapted to be rotated by means of a suitable worm 24, which engages worm teeth on the nut. By means of this construction, the center distance between the gear and the pinion may be accurately adjusted. 70

The universal mounting of the pinion 5 is well illustrated in Fig. 4. It will, of course, be understood that the floating frame 12 serves as a floating frame for the pinion 5 as a whole. The small floating frames 11 independently serve the half of the pinion which is supported by them. The horizontal frame or adjustable lever 18 serves to maintain the gear centers, but due to its mounting, does not interfere with the tilting motions of the rectangular frames 7 in any plane. 80

When the gearing is set up the various pivotal mountings of the rectangular and floating frames permit the bearings of the shaft 6 to automatically align themselves with each other and with other bearings of the gear set. In operation the friction of rest, due to the load imposed on the gearing, prevents the pivotal bearings from functioning. However, the I-beams on which the bearings are mounted provide sufficient flexibility to permit compensating movement of the floating frames when under load. 90

95 While I have shown my invention in but one form, it will be obvious to those skilled in the art that it is not so limited but is susceptible of various other changes and modifications, without departing from the spirit thereof and I desire, therefore, that only such limitations shall be placed thereupon as are imposed by the prior art or as are specifically set forth in the appended claims. 100

105 What I claim is:

110 1. In a gear set, the combination of a support, a floating frame, a flexible member carried by the support, and a pivotal connection between the floating frame and the flexible member. 115

120 2. In a reduction gear set, a mounting for at least one of the members of a gear set comprising a floating frame mounted so as to freely move to produce correct alignment when not under load, and separate flexible mounting means whereby the floating frame may move when under load. 125

130 3. In a gear set, a compound floating frame comprising a large floating frame, a flexible support therefor, a pivotal connection between the flexible support and the large floating frame, other floating frames, flexible members carried by the large floating

- frame, and pivotal connections arranged between the other floating frame and the last-mentioned flexible members.
4. In combination with gearing, a floating frame in which a gear member is mounted, and a lever pivoted to tilt in a plane substantially at right angle to the plane of the floating frame for maintaining the center distances of the gearing.
- 10 5. In combination with gearing, a floating frame in which a gear member is mounted, a lever pivoted to tilt in a plane substantially at right angle to the plane of the floating frame for maintaining the center distances 15 of the gearing, and means for adjusting the position of the lever.
6. A mounting means for a gear member comprising, a frame in which the gear member operates, a floating frame for permitting 20 tilting movements of said frame, pivotal means connecting said frame and the floating frame, flexible means for supporting the floating frame, and a pivotal connection between the flexible means and the frame.
- 25 7. A floating frame construction for gearing, comprising superimposed floating frames in one plane, universal mounting means therefor, and a lever pivoted to tilt in another plane and secured to at least one of 30 said floating frames.
8. A floating frame construction for gearing, comprising superimposed floating frames in one plane universal mounting means therefor, a lever pivoted to tilt in another plane and secured to at least one of 35 said floating frames, and an adjustable supporting arm pivotally attached to said lever.
9. In a floating frame construction for gearing, the combination of a floating frame, flexible means for supporting the frame, 40 whereby the frame may move under load, and a pivotal connection between the frame and the flexible member to secure no-load movements of the frame.
10. In a reduction gear, the combination 45 of pinion frames for the right and left hand helical pinion portions of the driving pinion, a floating frame, flexible members carried by said floating frame, other floating frames, pivotal connections between 50 said other floating frames and the flexible members, and pivotally connected strut members for connecting the pinion frames to said other floating frames.
11. In a reduction gear, the combination 55 of a plurality of pinion frames, a plurality of floating frames, pivotal connections arranged between the pinion frames and the floating frames, a floating frame for supporting said first mentioned floating frames, 60 a flexible member, and a pivotal connection arranged between the flexible member and the last mentioned floating frame.
- In testimony whereof, I have hereunto subscribed my name this 23d day of September, 1920.

R. C. ALLEN.
